United States Patent Office

Des. 233,080
Patented Oct. 1, 1974

233,080

EMBOSSED PLASTIC SHEET MATERIAL OR SIMILAR ARTICLE

Jared R. Kies, Newark, Ohio, assignor to Owens-Corning
Fiberglas Corporation

Filed Sept. 7, 1972, Ser. No. 287,171

Term of patent 14 years

Int. Cl. D5—06

U.S. Cl. D87—3 G

Fig. 1

Fig 2

FIG. 1 is a plan view of an embossed plastic sheet material showing my new design, a design unit being shown within the rectangle marked off, the repeat being indicated by the extensions beyond the border of the rectangle; and

FIG. 2 is an enlarged plan view of a portion of the design unit shown in FIG. 1 showing the embossment at substantially actual size.

I claim:

The ornamental design for an embossed plastic sheet material or similar article, substantially as shown and described.
